UNITED STATES PATENT OFFICE.

JAMES CLAYTON TINKER AND JOHN HART ARRAN, OF LEEDS, ENGLAND.

MILLING-MACHINE FOR CLOTH.

SPECIFICATION forming part of Letters Patent No. 716,147, dated December 16, 1902.

Application filed May 6, 1902. Serial No. 106,148. (No model.)

To all whom it may concern:

Be it known that we, JAMES CLAYTON TINKER and JOHN HART ARRAN, subjects of the King of Great Britain and Ireland, residing at Leeds, in the county of York, England, have invented new and useful Machinery for Milling, Scouring, and Crabbing Textile Fabrics, of which the following is a specification.

This invention relates to an improved natural milling-machine with which is combined apparatus for scouring and crabbing for the purpose (in one machine) of milling, scouring, and crabbing vicunas, worsted coatings, serges, tweeds, rugs, shawls, blankets, or other fabrics manufactured from botany, saxyony, crossbred, high or low class woolen or other yarns. Hitherto these processes have been carried out in separate machines, entailing great labor and loss of time.

20 Our invention is illustrated in the accompanying drawings, in which—

Figure 1 is an end elevation, and Fig. 2 a side elevation, of the machine.

In constructing our improved machine we provide a large bowl *a*, catch-box *b*, and pair of wooden or iron rollers *c c*, which may be either bare or padded. A pair of adjustable milling-boards *d* and *e* of any approved construction are provided, these being either plain, corrugated, convex, or concave and being employed either stationary or in any required position, or with a rocking motion produced by means of suitable cranks or eccentrics. (Not shown.) On these boards the natural mill is obtained—that is to say, the goods are milled without the aid of any weight, pressure, or force of any kind other than that obtained from the rollers *c c*. The rollers *c c* are carried by a pair of standards *f f*, which are fixed on sole-plates *g*, placed along each side of the bowl *a*. At the top of each standard *f* is a suitable wheel *h* or other device for applying pressure to the rollers *c c* when required.

45 The machine may be driven direct in the usual way by means of fast and loose pulleys on the bottom roller-shaft *k*. Preferably, however, it is driven from a counter-shaft *l* by means of fast pulley *i*, loose pulley *j*, and 50 gear-wheels *m* and *n* thereon and corresponding gear-wheels *o* and *p* on the shaft *k*, the

wheels *m* and *n* being fitted on a loose sleeve *q*, which slides on feather-keys *r r*, fitted in the end of the counter-shaft *l*. By this arrangement two speeds are obtained—a quick 55 speed for the milling operation and a slow speed for the crabbing operation—as may be desired. Levers *s* and rack-and-pinion gear *t t*, operated from the wheel *u*, are provided for raising and lowering the crabbing-roller 60 *v*. A steam-pipe *w* is also provided at the rear of the machine for open steam-blowing during the crabbing process when required. Suitable brake-rollers are fitted at the rear of the machine; also, a drawing-roller *x* in front 65 for goods not requiring to be milled. The brake-roller arrangement consists, preferably, of a fixed roller *y* and loose roller *z*, carried by arms *l* on an intermediate shaft *2* and operated by means of a handle at one end, so 70 as to be interchangeable in position for the purpose of varying the braking power.

The operation of the machine is as follows: The goods are placed on the machine in the ordinary manner, passing between the main 75 rollers *c c*, then over the adjustable milling-board *d*, under the supplementary milling-board *e*, over the brake-roller, and back to the rollers *c c*, or for ordinary scouring the goods may be passed through the main rollers *c c*, 80 over the draw-roller *x*, through the bowl *a*, over the brake-roller, and back to the rollers *c c*. When these processes are completed, a crabbing-roller *v* is placed in position on the lever *s*, and pressure is applied to the top 85 roller *c* by means of the wheels *h*. If the goods require also to be steam-blown, the steam is applied by means of the perforated pipe *w*. After the completion of these processes the crabbing-roller *v* is lowered to the 90 top of the bowl *a* by means of the wheel *u*, rack-and-pinion gear *t t*, and lever *s* and is placed in the extended arms *3* ready to be taken away to the tentering-machine, the goods having been milled, scoured, crabbed, 95 and steam-blown in one machine.

What we claim as our invention, and desire to secure by Letters Patent, is—

In a machine for milling, scouring and crabbing textile material, the combination, with 100 a bowl, and a catch-box in the upper part of the bowl; of main rollers arranged one above

the other over the catch-box, means for supporting and driving the said rollers, milling-boards arranged in the said bowl, a crabbing-roller supported on one side of the said main rollers, means for raising and lowering the said crabbing-roller, a draw-roller supported above the said crabbing-roller and on the same side of the said main rollers, and brake mechanism arranged on the opposite side of the said main rollers from the said crabbing-

roller and draw-roller, substantially as set forth.

In testimony whereof we have signed our names to this specification in the presence of two subscribing witnesses.

JAMES CLAYTON TINKER.
JOHN HART ARRAN.
